JULIUS I. LIVINGSTON, OF PITTSBURG, PENNSYLVANIA.

Design No. 3,539, dated June 15, 1869.

DESIGN FOR A TRADE-MARK

The Schedule referred to in these Letters Patent and making part of the same.

To all whom it may concern:

Be it known that I, JULIUS I. LIVINGSTON, of Pittsburgh, in the county of Allegheny, and State of Pennsylvania, have invented a new and valuable Design for Trade-Mark; and I do hereby declare that the following is a full, clear, and exact description of the same, reference being had to the annexed drawings, making a part of this specification.

My trade-mark consists of a monogram, set in a figure of the form shown, and having arranged upon its borders the words "Crystal Petroleum Works, Pittsburgh, Livingston Bros."

What I claim as my invention, and desire to secure by Letters Patent, is—

The design for a trade-mark herein set forth and shown.

In testimony that I claim the above, I have hereunto subscribed my name, in the presence of two witnesses.

JULIUS I. LIVINGSTON.
